ROSS M. G. PHILLIPS, OF WEST HAVEN, CONNECTICUT, ASSIGNOR TO THE SENTINEL AUTOMATIC GAS APPLIANCE CO., OF NEW HAVEN, CONNECTICUT, A CORPORATION.

SINGLE-BURNER FLAT-IRON HEATER.

1,109,936.

Specification of Letters Patent. Patented Sept. 8, 1914.

Application filed March 27, 1914. Serial No. 827,530.

To all whom it may concern:

Be it known that I, Ross M. G. Phillips, a citizen of the United States, residing at West Haven, in the county of New Haven 5 and State of Connecticut, have invented a new and useful Improvement in Single-Burner Flat-Iron Heaters; and I do hereby declare the following, when taken in connection with the accompanying drawings and 10 the characters of reference marked thereon, to be a full, clear, and exact description of the same, and which said drawings constitute part of this application, and represent, in—

Figure 1 a plan view of an automatic single-burner flat-iron heater constructed in accordance with my invention. Fig. 2 a view thereof in front elevation with a flat-iron indicated by broken lines in position for being heated. Fig. 3 a view in vertical 15 transverse section on the line *a*—*b* of Fig. 1. Fig. 4 a view of the heater in vertical longitudinal section on the line *c*—*d* of Fig. 1. Fig. 5 a schematic view showing a flat-iron being heated with the iron-operated valve- 20 operating lever in its normal or elevated position in which the gas-valve is open. Fig. 6 a schematic view showing the burner extinguished by the use of a cold flat-iron for depressing the iron-operated valve- 25 operating lever. Fig. 7 a schematic view showing the nose of a hot flat-iron engaged with one side of a cold flat-iron preparatory to pushing the latter off the lever to release the same for the relighting of the burner. Fig. 30 8 a schematic view showing the cold flat-iron as pushed over the burner by the nose of the hot flat-iron, the iron-operated lever released and the burner re-lighted.

My invention relates to an improved gas-burning flat-iron heater, the object being to provide a simple and convenient device for the heating of a single iron at a time, two irons being used alternately and the flame being automatically extinguished prior to 40 the removal of the heated iron from the heater to guard against the scorching of the hands of the ironer.

With these ends in view, my invention consists in a gas-burning flat-iron heater 45 having certain details of construction and combinations of parts as will be hereinafter described and pointed out in the claims.

In carrying out my invention as herein shown, I employ an iron-operated valve-

operating member 2 in the form of a lever 55 having a flat-iron arm 3 which is normally lifted above the horizontal plane or working surface 4 of an oblong gridiron or grill 5 supported upon an oblong heater-frame 6 having legs 7 at its corners. The said lever 60 2 is mounted upon a rock-shaft 8 located below the grill 5, journaled at its ends in the said frame 6 and having the outer end of the lever 2 secured to it by a screw 9. At its inner end the lever 2 is formed with 65 a clearance notch 10 and is turned downward to produce a supporting-arm 11 having a notch 12 adapting the said arm to be engaged with the forward end of a horizontal valve-actuating lever 13 hung upon a 70 screw-stud 14 and having its rear end slotted as at 15 for the reception of the cranked end 16 of the rotary valve-stem 17 of a normally closed valve 18. A helical spring 19 connected with the lever 13 in front of the 75 screw-stud 14 exerts a constant effort to hold the lever 2 in its elevated position in which its arm 3 extends above the plane 4 of the grill 5. In this position of the lever 2, the valve-stem 17 is turned by the lever 80 13 into position for closing the valve 18 which has a T-shaped valve-body the inlet-end of which is provided with a gas-connection 19 leading to any convenient source of gas-supply. The said inlet-end of the valve 85 18 is formed with a pilot-light nipple 20 having a regulating-screw 21 as shown in Fig. 1. From the nipple 20, a small pilot-light tube 22 leads forward to the left hand side of a burner 23 which is provided along 90 its edges with a series of burner-nipples 24. The outlet-end of the valve 18 is furnished with a regulating-screw 25 and enters a conical mixing-chamber 26 cast integral with the rear end of the burner which is 95 also cast with two integral, alined hubs 27 one of which receives the screw-stud 14 of the lever 13. The burner 23 extends from front to rear under a burner-frame formed integral with and depending from the grill 100 5 and comprising side bars 28 and cross-bars 29. The burner-frame forms, as it were, the central portion or heating-section of the grill 5 the right hand end of which may be called its shut-off section, and its 105 left hand end, its storage-section. The forward ends of the side bars 28 are extended to form suspension-lugs 30 resting upon the

front of the heater-frame 6 and at their rear ends to form suspension-lugs 31 resting upon the rear side thereof. The front cross-bar 29 is extended downward as at 32 to form a bracket receiving a suspension-stud 33 located at the forward end of the burner 23 the rear end of which is provided with an upwardly extending suspension-flange 34 fastened by a screw 35 to the rear of the heater-frame 6. To prevent the lateral displacement of the valve-operating lever 2, the right hand bar 28 of the burner-frame is formed with a pair of vertical lugs 36 between which the inner end of the lever 15 plays up and down.

As shown, the right hand end of the heater-frame 6 is furnished with upstanding guard lugs 37 while the overhanging left hand end of the grill is provided with 20 corresponding but smaller guard lugs 38.

The operation of my improved flat-iron heater is graphically illustrated by schematic Figs. 5 and 8 inclusive of the drawings. Gas having been turned on at the source of supply and lighted at the burner 23, a flat-iron A is set upon the burner-frame forming the middle or heating-section of the grill 5 in position to clear, as shown in Figs. 4 and 6, the upstanding-arm 3 of the lever 2 which 25 is for this purpose formed with the notch 10 as described. When the iron A is hot, a cold iron B is placed upon the right hand end or shut-off section of the grill 4, whereby the lever 2 is depressed by its flat-iron 30 arm 3 against the tension of the spring 19 and the valve 18 closed so as to shut off the supply of gas to the burner 23, and extinguish the flame thereat as shown by schematic Fig. 6, except for the pilot-light. The 35 hot iron A may now be removed by the ironer without any danger of scorching her hand, since the flame has been extinguished. The nose of the hot iron A is now used, as shown in schematic Fig. 7, to push the cold iron B over upon the burner-frame or heating section of the grill 5, and hence over the burner 23 which is now immediately re-lighted from the pilot-light owing to the 40 fact that the lever 2 is released to the action 45 of the spring 19 which operates the lever 13 in opening the valve 18 which then begins to supply gas to the burner 23 as shown in Fig. 8. Of course the particular method of use will be varied within limits according to 50 the pleasure of the ironer using the heater. Ordinarily two irons will be simultaneously heated in the first place by being arranged side by side over the burner 23 lengthwise of the grill 5. Being placed lengthwise, they 55 will clear the lever 2 and permit the same 60 to remain in its elevated position in which the gas valve 18 is left open, the arm 3 of

the lever 2 then standing up between the adjacent sides of the two irons.

I claim:—

1. In a gas-burning flat-iron heater, the combination with a grill, of a burner located beneath the same, a valve for the burner, a flat-iron operated valve-operating member normally rising above the plane of the grill in position to be cleared by a flat-iron when the same is in position to be heated, and means for connecting the said valve and member for automatically closing the former by the depression of the latter. 75

2. In a gas-burning flat-iron heater, the combination with a grill, of a burner located beneath the same, a valve for the burner, a pivotal flat-iron operated valve-operating lever pivoted below the grill and normally rising above the plane thereof in position to be cleared by a flat-iron when the same is in position to be heated, means connecting the said valve and lever for automatically closing the former by the depression of the latter, and a spring normally maintaining the lever in its elevated position. 85

3. In a gas-burning flat-iron heater, the combination with a grill comprising a shut-off section, a storage section, and an intermediate heating section, of a burner located below the said heating section, a valve for the burner, pilot-light connection between the valve and the burner, a valve-operating member normally projecting above the plane of the grill in position to be cleared by a flat-iron when the same is in position to be heated, connection between the said valve which is normally open, and the said member, and a spring for maintaining the said member in its normally elevated position, whereby when a flat-iron is placed upon the said member to depress it the valve will be closed and the flame in the burner extinguished. 95

4. In a gas-burning flat-iron heater, the combination with a grill, of a burner, a valve therefor, a valve-operating lever pivoted beneath the grill and normally extending above the plane thereof in position to be cleared by a flat-iron when the same is in position to be heated, a valve-actuating lever between the said valve-operating lever and valve, and a spring normally maintaining the valve-operating lever in its elevated position and the valve open. 110

In testimony whereof, I have signed this specification in the presence of two subscribing witnesses.

ROSS M. G. PHILLIPS.
